(57) **CLAIM**

The ornamental design for a flexible docking cable for mobile device, as shown and described.

DESCRIPTION

FIG. 1 is a perspective view of a flexible docking cable for mobile device showing our new design, shown in an environment and position of use;

FIG. 2 is a perspective view of a flexible docking cable for mobile device;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings represent portions of the article and environmental subject matter which form no part of the claimed design. The broken away symbols in the drawings indicate the appearance of any portion of the article between the break lines forms no part of the claimed design.

1 Claim, 5 Drawing Sheets
